UNITED STATES PATENT OFFICE

HUGH M. ROCKWELL, OF ELMHURST, NEW YORK

INTERNAL-COMBUSTION ENGINE

Application filed October 7, 1925. Serial No. 61,077.

This invention relates to internal combustion engines and has for an object a highly efficient valve actuating means suitable for use in the engine which is the subject matter 5 of applicant's copending application Ser. No. 46,835, filed July 29, 1925.

According to the invention, the valve is actuated by a rocker, one end of which is engaged by one end of a tappet rod which bears 10 at its other end directly against a cam thus obviating the need of a cam follower guide. The rocker is mounted in a housing which is adjustably mounted on one end of a tube, the other end of which is adjustably mounted 15 on the crank case. The housing is also connected to a cylinder by a link. The tube surrounds the tappet rod and by means of it, the rocker arm housing may be adjusted to obtain the proper clearance between the tappet 20 rod and rocker or cam. The cams are formed on a sleeve rotatably mounted concentric with the crank shaft and driven therefrom through suitable gearing.

Referring now to the drawings, 25 Fig. 1 is a vertical section showing the valve, rocker arm, and tappet rod relationship.

Fig. 2 is a section on line 2—2 of Fig. 1.

Fig. 3 is an end elevation of the cam support and tappet rod guide.

Fig. 4 is a side elevation thereof.

Fig. 5 is a vertical section therethrough.

Figs. 6 and 7 show the tappet rod structure.

Fig. 8 discloses the tappet rods in their relationship to the cam and guide member, and Fig. 9 is a section on line 9—9 of Fig. 8.

In applicant's copending application, Ser. No. 46,835, filed July 29, 1925, is shown an 40 engine to which the hereinafter described valve actuating mechanism is particularly adapted. In said application is disclosed a substantially cylindrical casing C from which project a plurality of cylinders. One of these 45 cylinders is represented at 10 in Fig. 1 and is provided in its outer end with a pair of valves, only one of which 11 is disclosed in this figure, the other being a substantial duplicate. The stem of valve 11 is hollow and is slidably 50 mounted in a guide member 12 mounted on

the cylinder. At the end of the valve stem is mounted a collar 13 between which and an abutment 14 on the member 12 is arranged a pair of concentric helical valve operating springs 15 and 16, the inner of which is made 55 of smaller diameter wire than the outer. In the end of the valve stem is frictionally held a plug 17.

A two part housing 18 is supported from the crank case C by a tube 19 having one end threaded into a clamp collar 20 formed in one section of the housing, the adjoining parts of the two sections of the housing having formed therein semi-spherical sockets which, when the two parts are joined together by the bolts 21 form a spherical recess. In this recess is rotatably mounted a spherical member having arms which constitute a rocker 22. One end is in contact with the plug 17 and the other end engages the end of a tappet rod to be later described. The end of the rocker 22 in contact with the tappet rod engages guide members 22a projecting from the interior of the housing 18. A link 23 connects the housing 18 to the valve support 12. The other end of the tube 19 is provided with a flange 24 seated in a socket in the crank case C and is held in place by a nut 25 threaded into the socket. The bottom of the socket and the face of the flange are rounded to permit proper inclination of the tube at different adjustments of the tube in the housing. The housing 18 acts as a fulcrum for the rocker 22 and may be adjusted relative to the crank case by means of the tube 19.

A hollow tappet rod 26 is slidably mounted in the tube 19, the bore of which gradually increases from top to bottom, and has one end engaging an end of the rocker 22 and the other end operatively related to a cam member to be described later.

Supported by a wall of the crank case C is a hollow shaft 27. This shaft has a threaded portion extending through the wall on which is provided a nut 28. Rotatably mounted on shaft 27 is a sleeve 29 which is driven from the crank shaft by a planetary reduction gearing in the manner described in applicant's copending application, Ser. No. 61,076, filed October 7, 1925. Cams 30 and 31

project from the surface of the sleeve 29 and a timing gear 32 is provided to operate a distributor. A cup-shaped member 33 is clamped against the wall of the crank case 5 by the shaft 27 and substantially surrounds said shaft. In this member is provided a plurality of guides 34 through which project the ends of the tappet rods 26. A key 35 prevents rotation of the members 27 and 33.

10 The shaft 27 and nut 28 serve to locate and lock in place the sleeve 29 and member 33.

The end of the tappet rod 26 is bifurcated to receive a roller 36 having studs 37 seated in semi-circular grooves in the end of the rod.

15 The roller is held in place by a wire 38 passing through a hole in the rod and bent down along the sides thereof, the ends of the wire being bent to enter holes in the studs 37. These wires also fit in grooves 39 in the tubu- 20 lar members 34 to prevent rotation of the tappet rods. The tappet rods are thus always maintained with the rollers in alignment with the cams 30 and 31 on the sleeve 29.

The above described rocker arm support 25 obviates the need of a separate cam follower and guide and permits the use of a tappet rod of a definite length. In order to get the adjustment of the rocker relative to the tappet rod and valve stem for proper clearances, 30 the nut 25 and the clamp collar 20 are loosened to permit turning the tube 19. The housing 18 may thus be drawn toward or moved away from the crank case pivoting on the link 23 until the proper adjustment 35 is obtained. The curved contacting surfaces of the flange 24 and the socket receiving it allow the tube 19 to assume the proper inclination for its adjusted position and the tapered bore of the tube insure proper clearance between the tappet rod and its inner 40 surface.

It is, of course, understood that various changes may be made in structure without departing from the spirit of the invention as 45 set forth in the appended claims.

What is claimed is:

1. In an internal combustion engine, a crank case, a cylinder carried thereby and having a port, a valve for said port, a housing 50 adjustably supported from said crank case, means for pivotally connecting said housing to said cylinder, a rocker mounted in said housing and operatively related to said valve, a cam, and a tappet rod for said 55 rocker contacting with said cam.

2. In an internal combustion engine, a crank case, a cylinder carried thereby and having a port, a valve for said port, a rocker for operating said valve, a housing supporting 60 said rocker, means for pivotally connecting said housing to said cylinder, a tubular member mounted on said crank case, adjustable supporting connections between said tubular member and said housing, a cam, and 65 a tappet rod for said rocker mounted in said

tubular member and contacting with said cam.

3. In an internal combustion engine, a crank case, a cylinder carried thereby and having a port, a valve therefor, a tubular member supported by said crank case, a housing adjustably supported by said tubular member, means for pivotally connecting said housing to said cylinder, a rocker arm for actuating said valve mounted in said housing, a cam, and a tappet rod for said rocker arm contacting with said cam. 75

4. In an internal combustion engine, a crank case, a cylinder having a port, a valve therefor, valve supporting means, a tubular member having a flanged portion seated in a socket in said crank case, the contacting surfaces of said flange and socket being rounded, means to hold said flange in said socket, a housing adjustably mounted on the end of 80 said tubular member, a rocker for said valve mounted in said housing, a cam and a tappet rod for said rocker having one end contacting with said cam. 85

5. In an internal combustion engine, a crank case, a cylinder having a port, a valve therefor, valve guiding means, a tubular member having a flanged portion seated in a socket in said crank case, the contacting surfaces of said flange and socket being rounded, 90 means to hold said flange in said socket, a housing adjustably mounted on the end of said tubular member, a link connecting said valve guiding means and said housing, a rocker for said valve mounted in said housing, a cam and a tappet rod for said rocker having one end contacting with said cam. 95

6. In an internal combustion engine, a crank case, a cylinder carried thereby and having a port, a valve for said port, a rocker for operating said valve, a housing supporting said rocker, means for pivotally connecting said housing to said cylinder, a cam in said crank case, a tappet rod of fixed length interposed between said rocker and said cam, 100 and an adjustable supporting member for said housing surrounding said tappet rod. 110

In testimony whereof I hereunto affix my signature this 5th day of October, 1925.

HUGH M. ROCKWELL.
